UNITED STATES PATENT OFFICE

MAX WENZEL, OF MULDENSTEIN, NEAR BITTERFELD, GERMANY

ROLL SUCTION DEVICE

Application filed December 8, 1930, Serial No. 500,774, and in Germany December 16, 1929.

This invention relates to roll suction devices, and with regard to certain more specific features to suction boxes for rolls used in the manufacture of paper.

5 Among the several objects of the invention may be noted the provision of a device of the class described in which a suction box is divided into separate compartments for air and for water; the provision of a device of the 10 class described in which there is provided a separate trough or sump placed within a suction box; the provision of a device of the class described in which there is provided means for relieving the said trough or sump of air 15 pressure, thereby permitting it to be more economically made, even though it be composed of a non-corroding and therefore more expensive materials; the provision of a device of the class described in which there is 20 provided means which reduces the formation of injurious deposits of paper pulp and the like; and the provision of a device of this class which is simple, effective, and which finds a wide application in different sizes 25 and types of apparatus. Other objects will be in part obvious and in part pointed out hereinafter.

The invention accordingly comprises the elements and combinations of elements, features of construction, and arrangements of parts which will be exemplified in the structure hereinafter described, and the scope of the application of which will be indicated in the following claims.

35 In the accompanying drawings, in which are illustrated several of various possible embodiments of the invention,

Fig. 1 is a diagrammatic, longitudinal section of a suction box and roller;

40 Fig. 2 is a cross section showing successive suction boxes and rollers, the section at the left of the figure being taken in plane A—A of Fig. 1 and the section at the right being taken in plane B—B of Fig. 1;

Fig. 3 is a longitudinal section corresponding to Fig. 1 and showing a second embodiment of the invention; and,

45 Fig. 4 is a view similar to Fig. 2 showing the second embodiment of the invention, the

left and right sections being taken on lines C—C and D—D of Fig. 3, respectively.

Similar reference characters indicate corresponding parts throughout the several views of the drawings.

55

Referring now to the drawings, and more particularly to the embodiment illustrated in Figs. 1 and 2, there is represented at numeral 1 a screen or sieve on which a wet web of paper pulp is disposed and from which water is to be removed. A number of rollers 3 carry screen 1 and are transversely mounted therebeneath. Below the rollers 3 there is provided a series of suction boxes 5 provided with longitudinal packing ledges 7, said ledges forming a substantially air-tight, water seal between the rotating rollers 3 and the box 5.

60 Within the suction boxes 5 and between and along the ledges 7, sumps or chutes or troughs 9 are disposed. These chutes 9 may conveniently be supported between the upper edges of the suction boxes 5 and the lower edges of the packing ledges 7, and are preferably made of some non-ferrous, non-corro- 65 sive material such as brass, copper, or the like. The troughs are preferably shaped so as to have smooth lateral walls as steep as possible and a rounded bottom portion.

70 It will be noted that the bottoms of these troughs 9 are held in a longitudinal and inclined position with respect to the suction boxes 5 and the rollers 3, and terminate at their lowermost portions in discharge suction tubes 11 which are placed at one end of the suction boxes 5.

75 At the other end of the suction boxes there are provided a second set of discharge suction tubes 13. The bottoms of the troughs 9 are therefore each inclined from above tube 13 towards tube 11 with the upper edges of the troughs fastened to the horizontal top edges of the suction boxes 5. The troughs 9 therefore divide the suction boxes 5 into two compartments 15 and 17. The upper compartments 15 are defined by the troughs themselves; the lower compartments 17 are defined by the walls of the boxes 5 and the troughs 9.

80 The discharge suction tubes 11 are connected to a pump or other device so as to 85

90

95

100

produce a partial vacuum within the compartments 15. Inasmuch as this vacuum also extends throughout the volumes defined by the packing ledges 7 and rollers 3 (see Fig. 2) it is clear that there is an air pressure acting downwardly on the wet mat of paper pulp on screen 1. This pressure forces water in the wet mat down through the screen 1 into troughs 9 and it is discharged through the tubes 11.

The suction water 19 passing through the screen 1 incidentally carries with it some of the paper pulp and is sometimes called "white water". Inasmuch as the bottoms of troughs 9 are mounted in an inclined position and are rounded there is little or no opportunity for quantities of the pulp to settle out of the "white water" and collect within the troughs. The suction water is afforded a constant and smooth flow with little opportunity to form eddy currents which would produce deposits of the paper pulp as may be formed where an ordinary suction box is used.

In addition to the "white water" which comes through the screen 1 there is also some air sucked through. For the purpose of discharging this air, there are provided the suction tubes 13 and by-pass openings 21 in the sides of the troughs 9. These openings 21 are above the level of the water 19 and by-pass the suction air from chamber 15 into chamber 17. A suction is created in chamber 17 by communication with the suction tube 13. The suction air entering chamber 15 along with the suction water 19 is therefore free to pass from chamber 15, through the openings 21, into chamber 17, and out through the discharge tube 13, as shown by the arrows. Thus it is seen that the tube 11 discharges the "white water" and the tube 13 discharges air.

To prevent quantities of the "white water" which follow the packing ledges 7, or drippings from the rollers 3 or screen 1, from being carried along with the discharge air, the portions of the walls of the troughs 9 which are located beneath the openings 21 are bent outwardly towards the walls of the suction boxes 5, as shown at numeral 23 (Fig. 2), thus providing a shingle effect. The same result obtains if the wall portions are bent as shown at numeral 25 (Fig. 2).

The troughs 9 are substantially relieved of air pressure and are subjected to only the weight of the water 19. This condition exists because the chambers 15 and 17, which are separated by the troughs 9, are both suction chambers. The troughs 9 may therefore be more economically made. A further economy arises in that the design of the troughs 9 is independent of the material and shape of suction boxes 5. The suction boxes 5 may be made of iron or some material cheaper than the troughs 9. Inasmuch as the suction water is confined within the troughs 9, problems of corrosion and the like of the boxes

5 are practically eliminated, and the non-corroding sump or trough which is made of more valuable materials may be made lighter, because it is not subjected to a substantial pressure differential within and without. 70

In the embodiment shown in Figs. 3 and 4, the same reference numerals as are used in Figs. 1 and 2 are used to designate parts performing the same functions as the parts of Figs. 1 and 2. 75

Several differences in the structures of the two embodiments exist. Instead of the discharge tubes 11 and 13 leaving the suction to boxes 5 perpendicular to the rollers 3, these tubes are parallel to the rollers. Also the suction boxes 5 are round instead of square or rectangular, and the packing ledges 7 are closer together and are juxtaposed with respect to a pair of rollers 3 instead of including therebetween a roller 3 as shown in Fig. 85 2. Instead of longitudinal openings 21 in the sides of the troughs 9, there are provided series of openings 26.

It will be noted that the positioning of the packing ledges 7 as shown in Fig. 4 produces a suction which is effective over a width b ; whereas Fig. 2 shows a positioning which produces a suction effective over a width a . Both widths are shown to illustrate the flexibility of design that is possible when using this invention. 90

It is to be understood that the suction for all the suction boxes and that the areas over which the suction of the boxes are effective are not necessarily the same. Furthermore, 100 the method of supporting the screen 1 may be varied. For example, the rollers 3 and the packing ledges 7 may be dispensed with, in which case the upper edges of the suction boxes 5 would be adjacent the screen 1. Furthermore, the openings 21 (Figs. 1 and 2) and 26 (Figs. 3 and 4) may be of many different shapes and may be distributed over the entire length or a portion only of the troughs 9. 110

It is also to be understood that the pipes 11 and 13 may join and deliver air and water to a common receptacle. Also, the suction may or may not be on the water discharge line. The discharge line may act as a plain 115 drain or as a suction liquid line.

In view of the above, it will be seen that the several objects of the invention are achieved and other advantageous results attained.

As many changes could be made in carrying out the above constructions without departing from the scope of the invention, it is intended that all matter contained in the above description or shown in the accompanying drawings shall be interpreted as illustrative and not in a limiting sense. 120

I claim:

1. In a device of the class described, a suction box, a discharge tube, and a trough, said trough being mounted within said box 130

- and being inclined towards and leading into said discharge tube.
2. In a device of the class described, a suction box, a discharge tube, and a trough, said trough being mounted within said box and being formed so as to lead suction water to said discharge tube.
3. In a device of the class described, a suction box, a discharge tube, and a trough, said trough being mounted within said box and packing ledges, said packing ledges being adapted to engage said trough so as to keep suction water from entering said box.
4. In a device of the class described, a suction box, a discharge tube, a trough within said box, and means for equalizing air pressure on said trough, said trough being adapted to deliver suction water to said tube.
5. In a device of the class described, a suction box, a trough, said trough being mounted in said box so as to divide said box into two compartments, a discharge tube communicating with one of said compartments for carrying away suction water, and a second discharge suction tube communicating with said second compartment for carrying away suction air.
6. In a device of the class described, a suction box, a trough, said trough being mounted in said box so as to divide said box into two compartments, a discharge tube communicating with one of said compartments for carrying away suction water, and a second discharge suction tube communicating with said second compartment, said trough having at least one opening communicating between said compartments, said second suction tube being adapted to discharge suction air from said first compartment by sucking said air through said opening into said second compartment.
7. In a device of the class described, a suction box, a trough, said trough being mounted within said box so as to divide said box into an upper and a lower compartment, a discharge tube, said trough delivering suction water to said tube, air suction means, and means for relieving said trough of substantial differential air pressure.
8. In a device of the class described, a suction box, a trough, said trough being mounted within said box so as to divide said box into an upper and a lower compartment, a discharge tube, said discharge tube communicating with said upper compartment and discharging suction water therefrom, and suction means communicating with said lower compartment; and means for relieving said trough of air pressure.
9. A roller suction device for paper machines comprising rollers, a screen carried by said rollers, a suction box beneath said rollers, a packing ledge adapted to seal said rollers and said box and a trough within said box and a trough being supported between said ledges and said box so as to exclude suction water from said box.
10. A roller suction device for paper machines comprising rollers, a screen carried by said rollers, a suction box beneath said rollers, a packing ledge adapted to seal said rollers and said box and a trough within said box, said trough being adapted to receive and discharge suction water coming from the material carried by said screen.
11. A roller suction device for paper machines comprising rollers, a screen carried by said rollers, a suction box beneath said rollers, a packing ledge adapted to seal said rollers and said box, a trough within said box and means for substantially equalizing pressure on said trough.
12. A roller suction device for paper machines comprising rollers, a screen carried by said rollers, a suction box beneath said rollers, a packing ledge adapted to seal said rollers and said box, a trough within said box, a discharge tube for carrying suction water away from said trough, and means for substantially equalizing pressure on said trough, said means comprising a suction pipe communicating with said box.
13. A roller suction device for paper machines comprising rollers, a screen carried by said rollers, a suction box beneath said rollers, a packing ledge adapted to seal said rollers and said box, a trough within said box, said trough being mounted within said box so as to divide said box into two compartments, a discharge tube for suction water communicating with one of said compartments and said trough, and a discharge tube for suction air, said second discharge tube communicating with said second compartment.
- In testimony whereof, I have signed my name to this specification this 25th day of November, 1930.
